SIDEWALK BENCH

David Flexer and Benjamin B. Sharer, Memphis, Tenn.

Application November 10, 1953, Serial No. 27,534

Term of patent 14 years

(Cl. D15—11)

Fig. 1.

Fig. 2.

Fig. 3.

To all whom it may concern:

Be it known that we, David Flexer, a citizen of the United States and Benjamin B. Sharer, a citizen of Great Britain, both residing at Memphis, in the county of Shelby and State of Tennessee, have invented a new, original, and ornamental Design for a Sidewalk Bench, of which the following is a specification, reference being had to the accompanying drawing, forming part thereof.

In the drawing:

We claim:

The ornamental design for a sidewalk bench, as shown.
